FOG AND TURNING LIGHT FOR
AUTOMOBILES AND THE LIKERobert B. Kuhn and Robert B. Kuhn, Jr.,
Canton, Ohio

Application December 29, 1949, Serial No. 6,905

Term of patent 14 years

(Cl. D48—32)

To all whom it may concern:

Be it known that we, Robert B. Kuhn and Robert B. Kuhn, Jr., citizens of the United States, residing at Canton, in the county of Stark and State of Ohio, have invented a new, original, and ornamental Design for a Fog and Turning Light for Automobiles and the like, of which the following is a specification, reference being had to the accompanying drawing forming part thereof, in which,

Figure 1 is a front elevational view of a fog and turning light for automobiles and the like showing our new design;

Figure 2 is a transverse sectional view thereof taken on the line 2—2 of Figure 1;

Figure 3 is a side elevational view thereof; and Figure 4 is a top plan view thereof.

The dominant features of our new design are shown in solid lines in the drawing.

We claim:

The ornamental design for a fog and turning light for automobiles and the like, substantially as shown and described.

ROBERT B. KUHN.
